UNITED STATES PATENT OFFICE

ALBERT S. GRAY, OF WENATCHEE, WASHINGTON, ASSIGNOR OF ONE-HALF TO JOHN DAVID CERTAIN, OF WENATCHEE, WASHINGTON

TIRE RIM BREAKING MACHINE

Application filed August 14, 1930. Serial No. 475,336.

This invention relates to improvements in tire rim contracting and expanding machines designed to facilitate the removal of tires from their rims and the placing of tires on their rims.

The primary object of the present invention is to provide a machine of the above described character, operated by an electric motor and so designed that the running of the motor will be stopped automatically when the rim upon which the machine is operating has been opened to the proper degree or when it has been expanded to the proper position in the tire.

Another object of the invention is to provide a machine of the above described character which is of simple and compact construction, strong and durable and having a minimum of moving or working parts.

The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a view in top plan of the machine embodying the present invention showing a tire rim in position thereon, a covering for the working parts being removed.

Figure 2 is a sectional view of the machine taken on the line 2—2 of Figure 1.

Figure 3 is a sectional view taken on the line 3—3 of Figure 1.

Figure 4 is a sectional view taken on the line 4—4 of Figure 1.

Figure 5 is a plan view of the underside of the cover for the working parts of the machine.

Figure 6 is a sectional view taken on the line 6—6 of Figure 1.

Referring more particularly to the drawings wherein like numerals of reference indicate corresponding parts throughout the sev-

eral views, the numeral 1 indicates a circular casing in which the moving parts of the present machine are housed, this casing being mounted upon supporting legs 2 which maintain it at a height convenient for an operator to place in position thereon or remove therefrom a tire rim such for example as is indicated by the numeral 3. This casing 1 is provided with a cover or lid 4 as shown in Figure 2, the edge of which is bordered by a flange 5 which overlies the outer face of the casing and maintains the top of the cover in position.

Within the casing 1 there are secured at diametrically opposite points the brackets 6 and 7, the bracket 6 having a central bar portion 8 connected to the wall of the casing by the angularly directed legs 9 while the bracket 7 has a central bar portion 10 which is parallel with the bar 8 and the short leg portions 11 which are obliquely directed as shown and connected with the casing wall in the same manner as the legs 9 connect the bar 8 to the casing. The parallel bars 8 and 10 are apertured on a line which passes through the radial center of the casing and connecting these bars and having its ends passing through the apertures thereof is a screw 12. One end of the screw is loosely mounted in the bar 8 while the other end has secured thereabout a pair of collars 13 which are disposed upon opposite sides of the bar 10 and prevent longitudinal movement of the screw.

Disposed between the bar 10 and the adjacent wall of the casing is a spiral gear 14 which has the adjacent collar 13 cast integral therewith, this gear being mounted upon and secured to the screw 12 as shown.

Secured to the supporting plate 15 which is mounted upon the underside of the casing 1 is an electric motor 16, the shaft 17 of which is vertically disposed and passes into the space between the bracket 7 and the casing wall. The upper end of this shaft 17 of the motor has a worm gear 18 mounted thereon which meshes with the gear 14.

Disposed adjacent and in spaced relation to each of the legs 11 of the bracket 7, and mounted upon the wall of the casing 1, is a

block 19 and each of these blocks has a passage formed horizontally therethrough in alignment with a similar passage formed in the adjacent bracket leg for the reception of a pin 20 which is inserted through an aligned tangential aperture in the wall of the casing, as shown in Figure 1.

The wall of the casing 1 is provided with a pair of apertures 21 each of which opens therethrough between a block 19 and a leg 11 and each of these apertures receives one end of an arm 22 which is provided with a plurality of apertures 23 one of which is aligned with the apertures through which the adjacent pin passes so as to permit the passage of the pin which holds the arm in position. Each of the arms 22 which extends radially from the wall of the casing 1 is enlarged at its outer end forming the head 24, one side of which head is formed to provide a hook 25 upon which an edge of the rim 3 may rest.

The wall of the casing 1 is provided with a second pair of apertures each of which is indicated by the numeral 26 and as shown each of these apertures is relatively wide and is located adjacent the outer side of a leg 9 of the bracket 6. Through each of the apertures 26 there extends a shiftable arm 25, the outer end of which is enlarged to form the head 28 which has at one side the integral hook 29 and at the other side the pivotally mounted hook 30 which coacts with the adjacent integral hook to grip the edges of the tire rim as clearly shown in Figure 3.

One of these arms 25 is of slightly greater length than the other, the difference in length amounting substantially to the thickness of the tire rim.

At their inner ends each of the arms 25 is reduced as indicated by the numeral 31 to form an ear which positions between a pair of similarly formed ears 32 formed at the end of a reciprocating block 33. This block 33 is provided with a central transverse threaded aperture in which is engaged the screw 12. A pivot pin 34 connects the ear 31 of the arms 25 with the spaced ears of the shiftable block, between which the ears of the arms are positioned.

From the description thus far given of the machine it will be seen that when the ends of the four radially directed arms are connected with a tire rim, with the rim so disposed as to position the split thereof midway between the ends of the shiftable arms 25, upon the operation of the motor 16 to turn the shaft 17 and the screw 12 in the right direction the arms 25 will be drawn inwardly. Since one of the shiftable arms is of greater length than the other, the increased length being in the hooks 29 and 30 thereof so that the arm will move a distance substantially equal to the thickness of the rim before the hooks begin to pull thereon, it will be readily

seen that one end of the rim will be drawn in before the other so that the breaking thereof may be effectively accomplished. It will, of course, be obvious upon a reversal of the operation of the motor the reverse operation will take place to restore the rim to its former condition.

The control switch for the motor 16 is mounted upon the lid 4 as indicated at 35 and there is also mounted upon the lid in circuit with the control switch, a reversing switch 36 so that the rotation of the motor 16 may be readily controlled. In order to protect the mechanism should the attendant of the machine not turn off the motor at the proper moment there are provided the cut-off switches 37 each of which is controlled by an arm 38. As shown in Figure 5 these arms are oppositely directed and each terminates in a right angularly extending portion 39 which portions are so disposed as to be in the path of travel of an end of the shiftable block 33. From this it will be readily obvious that when the mechanism is set into operation, as for example from the position shown in Figure 1, the reciprocating block 33 will move toward the remote angularly extending portion 39 of the remote arm 38 and when it comes into contact with this switch arm the switch will be opened and the circuit to the motor broken. When the tire rim is to be restored to normal condition the block 33, of course, travels in the opposite direction and then when it reaches the limit of its movement it comes into contact with the other switch control arm 38 opening this switch and breaking the motor circuit in the same manner.

It will, of course, be readily seen that by moving the normally fixed arms 22 inwardly or outwardly the machine may be adjusted to handle tire rims of any size.

Having thus described my invention, what I claim is:—

1. A tire rim breaking machine, comprising a circular casing, a pair of arms extending through the wall and radially of the casing, means for adjusting said arms radially of and securing them to the casing, a second pair of arms within and extending radially from the casing through the wall thereof, a connecting body between the adjacent ends of the last mentioned pair of arms, said arms being formed at their outer ends to engage and support a tire rim, a horizontally disposed screw member threadably extended through said body, a gear carried by said screw, an electric motor carried by said casing and having a worm connected with said gear, and switch control means for said motor.

2. A tire rim breaking machine, comprising a circular casing, a pair of arms extending through the wall and radially of the casing, a second pair of arms extending radially

of the casing, a connecting body between the adjacent ends of the last mentioned pair of arms, said arms being formed at their outer ends to engage and support a tire rim, a horizontally disposed stationary screw member threadably extended through said body, a gear carried by said screw, an electric motor suspended beneath and carried by said casing and having the armature shaft thereof vertically disposed and carrying a worm connected with said gear, switch control means for said motor, and means for adjusting said first mentioned pair of arms radially of and securing them to said casing to accommodate the machine to tire rims of different sizes.

3. A tire rim breaking machine, comprising a casing having a circular side wall, a pair of brackets disposed within the casing at diametrically opposite points, a screw member having its ends rotatably supported by said brackets and carrying a gear upon one end thereof, a block body having said screw extended therethrough and in threaded connection therewith, a pair of arms each connected at one end with said block and extending through the casing wall and provided at its other end with means for engaging a rim, a second pair of arms radially adjustable through said casing wall and disposed at opposite sides of a bracket and further having means at their outer ends for engaging a tire rim, a removable element coupling the inner ends of the last mentioned arms with the casing to maintain the arms in adjusted position, and power means connected with said gear for moving said block and the arms joined thereto.

4. A tire rim breaking tool, comprising a circular casing, a pair of brackets disposed at diametrically opposite points within the casing, a screw rotatably mounted between and supported by said brackets, a pair of arms extending radially from the casing through the wall thereof upon opposite sides of a bracket, a block member having threaded connection with the screw for movement thereby and having the inner ends of said arms pivoted thereto, a second pair of arms each extending radially through the casing wall and each having a longitudinally extending series of apertures therethrough at the inner end, pin members each removably extended through the casing wall and a portion of the last mentioned bracket and adapted to engage in an aperture of an adjacent arm, said arms being formed at their outer ends to engage a tire rim, and motor means for rotating said screw.

5. In a tire rim breaking machine, a casing, a screw disposed within said casing between the planes of the sides thereof, a block body mounted upon and having threaded connection with said screw to be moved there-

upon opposite sides of said screw and having pivotal connection with said body and further extending radially from said casing, said arms being moved with and by the body, a second pair of arms extending radially from the casing and fixed with relation to the first mentioned arms, a gear mounted upon one end of said screw, an operating motor having a pinion meshing with said gear, a pair of switch members each controlling the operation of said motor and disposed within the casing with said screw therebetween, each of said switches having an arm disposed substantially parallel to the screw and terminating in an inwardly directed portion, the inwardly directed portion of each switch arm being located adjacent one end of the screw to be engaged by the body upon its movement to that end, and means upon the outer end of each of said first mentioned arms for engaging a tire rim surrounding the casing.

In testimony whereof I hereunto affix my signature.

ALBERT S. GRAY.
